UNITED STATES PATENT OFFICE.

MORTON ARENDT, OF NEW YORK, N. Y., ASSIGNOR TO HEINRICH L. J. SIEMUND, OF NEW YORK, N. Y.

ELECTRIC-ARC WELDING.

Specification of Letters Patent.

Patented July 20, 1915.

1,146,989.

Application filed December 7, 1914. Serial No. 875,966.

No Drawing.

To all whom it may concern:

Be it known that I, MORTON ARENDT, a citizen of the United States, residing at and whose post-office address is Columbia University, borough of Manhattan, city, county, and State of New York, have invented certain new and useful Improvements in Electric-Arc Welding; and I do hereby declare the following to be a full, clear, and exact description of the invention, such as will enable others skilled in the art to which it appertains to make and use the same.

My invention comprises modifications in the art of electric arc welding, with the object of decreasing the size of the power-generating equipment required and increasing the efficiency of the operation. When an electric arc is fed directly by a constant potential system, the action of the arc is most erratic. The resistance of an arc decreases with increase of current, which results in a tendency for the current to become infinite if a constant potential is maintained across its terminals. Similarly, if the current begins to decrease, and to lessen the cross-section of the arc, the resistance increases and further chokes off the current until the arc goes out. This unstable characteristic of the electric arc on a constant potential circuit has led to the general practice of introducing a steady or balancing resistance in series with the arc. The use of such a resistance, while uneconomical, has been the general procedure in the case of electric arc welding; even though the energy consumption in the balancing resistance has been equal to or greater than the energy consumption in the arc. Thus, generators furnishing about seventy volts have been used where the voltage drop across the arc was only about 25 volts, the 45 volts excess being used up in the balancing resistance to produce a stable arc. This drop of 45 volts means a power loss directly proportional to the current employed, which, in metallic arc welding, for example, approximates 200 amperes, or a loss of nearly 9 k. w. out of 14 k. w. That is to say, only about 33% of the power supplied to the circuit is used to produce the arc.

I have carefully studied the phenomena of the arc, and realize that if some means can be introduced which will cause the voltage to fall as the arc stream increases in

cross section (i. e. current increases) the tendency for the current to approach an infinite value can be overcome; similarly if the arc stream tends to decrease in cross section (current fall) some rise in voltage will prevent this. However, to be satisfactory, this balancing action must not consume power. Furthermore, a constant current supply system will not answer the purpose, because, while a large current flow is necessary at striking the arc, to heat the point of contact and initiate rapid ionization, yet such a large current flow, if it continued as the arc is elongated, would rapidly melt or cut the metal to be repaired, and no metal could be deposited. The current value required at starting is much greater than the working current value; and, if continued, would cut the metal to be repaired and rapidly melt the repair electrode, in metallic electrode welding. In other words, the maximum current on short-circuit should be substantially less than would occur on a constant potential system, and should not exceed the predetermined maximum value required for initial heating. The maximum voltage on rupturing the arc should be much less than would occur on a constant-current system and should not exceed a predetermined maximum value, which is safe for the welder and is below the cutting voltage. I have discovered that these desirable conditions may be attained by causing the current variations accompanying alterations in the resistance of the arc to set up predetermined variations of the applied voltage in an opposite sense and of less extent than would be required to maintain a constant current. That is to say, by making such provision that as the arc resistance falls the applied electromotive force will be reduced somewhat, but not sufficiently to prevent a rise of current within the predetermined limits; and as the arc resistance rises the applied electromotive force will rise somewhat, but not sufficiently to prevent a current reduction within the predetermined limits.

A generator having the desired voltage-current characteristic may be secured by various methods, for example: A separately excited generator may be designed to supply about 30 volts on open circuit, while the combined effect of armature reaction and ar-

ture resistance drop at working current suffices to lower the terminal pressure to 25 volts, and on short circuit, the armature reaction and armature drop suffice to lower the voltage of the machine to such an extent that a current of about 300-350 amperes results. In such case quick response to the changes of arc current would be hastened by using a laminated field structure. Another way of accomplishing the same result without exaggerated armature reaction, is to employ a generator with field excitation produced by current from an external source and also by a shunt winding, the separate excitation and shunt excitation being so proportioned that in short circuit the failure of the shunt excitation lowers the machine voltage so that the short circuit current will not rise to an objectionable value, while the increase of the machine voltage on lengthening the arc is limited to a safe value through the saturation hastened by the separate excitation. A third method is to use a separately excited machine, provided with a weak differential winding, sufficient to limit the current on striking the arc to the safe starting value, or in place of the differential winding, a machine provided with interpoles may be employed and the differential result accomplished by shifting the brushes slightly from the neutral position. I have listed several control methods, though others exist in the

art, and are known to any competent designing engineer.

In practising this method of welding, I have used a separately excited generator which on open circuit gave about 30 volts and when operating with an arc current between 150-200 amperes the voltage was about 22, while on short circuit the current was about 400 amperes. This large value of current on short circuit existed only during the moments of starting the arc and the voltage across the arc at the moment of inception was of such low value that burning of structure did not result.

What I claim is:

The method of electric arc welding or repairing which consists in striking the arc between an electrode and the metal to be repaired and causing current variations accompanying alterations in the resistance of the arc to vary the voltage applied to the circuit in the opposite sense and to an extent substantially less than would be required to maintain a constant current, whereby the large initial heating current which flows at the instant of striking the arc is reduced and maintained as a steady working current.

In testimony whereof I affix my signature, in presence of two witnesses.

MORTON ARENDT.
